BILLBOARD FRAMING AND BLANKING
MEANS

Stephen Chase, IV, Kenilworth, Ill.

Application January 23, 1939, Serial No. 252,338

6 Claims. (Cl. 40—125)

This invention resides in a novel means for use in or as a part of display installations, such as billboards, in connection with the mounting or displaying of posters or the like thereon.

5 A general object of the invention is the provision of such a display means of a character which may be produced very economically, and installed at low cost on bill boards of various types and sizes, and which may be employed effectively to improve the appearance of the installation and at the same time decrease the cost of maintaining it by eliminating any necessity for wooden or other types of frames or borders which require periodic painting.

15 Another object of the invention is the provision of such a display means which may be mounted upon a billboard or the like by use of instrumentalities commonly employed in bill posting, in such a fashion as to form, in appearance, an effective border or frame that will give the installation desirable aspects of finish, neatness and substantiality.

25 Yet another object is the provision of such a display means which may be produced in quantities at low cost per unit of area and in a form and character such as to facilitate its installation and permit its being securely retained in place on billboards and the like by adhesives of the kinds commonly employed in bill posting.

30 Other and further objects of the invention will be pointed out or indicated hereinafter, or will be apparent upon an understanding of the invention or its employment in practice.

35 For the purpose of aiding in an explanation of the invention, I illustrate in the accompanying drawings forming a part of this specification, and hereinafter describe, certain forms and manners in which the invention may be embodied and practiced. It is to be understood, however, that 25 these are presented merely by way of example, and hence are not to be construed in any fashion for the purpose of limiting the appended claims short of the true and most comprehensive scope of the invention in the art.

45 In said drawings:

Fig. 1 is a front or elevational view, slightly in perspective, of a billboard installation which includes as a part thereof framing means constituting the subject matter of the present invention;

50 Fig. 2 is a detail, in the nature of a front view of a corner portion of a border or frame formed of combined framing and blanking strips constituting the subject matter of this invention;

55 Fig. 3 is an illustration similar to Fig. 2 but

showing the strips of a somewhat different character;

Fig. 4 is a detail, in perspective, illustrating a rolled margin strip in accordance with the invention and serving to illustrate one manner in 5 which it may be manipulated for application to a billboard;

Fig. 5 is a perspective view of a printing or lithographing cylinder which may be employed for printing margin strips in accordance with 10 the method constituting part of the invention;

Fig. 6 is a diagrammatic illustration of printing or lithographing apparatus and associated elements such as may be employed for producing margin strips embodying the present invention; 15 and

Fig. 7 is a surface view of a portion of a web of paper or the like which has been printed or lithographed to produce my improved margin strips in multiple and serving to illustrate the 20 product in an intermediate or unfinished state.

As indicated above, the invention pertains generally to display posting, as for example the advertising displays or the like which are posted on billboards, and it is to be understood that 25 when I hereinafter refer to billboards, the term is to be regarded as including not only installations built originally and specifically for that purpose, but also those which have been adapted to that use, though originally or primarily made 30 for other purposes, such as walls, etc. However, the present invention is concerned definitely with such posting displays which are of large size, as for example outdoor billboards which generally are of dimensions of the order of 25 35 feet by 11 feet.

The display space afforded by such billboards is customarily rented by the proprietors thereof to persons who wish to use it for displaying posters, most commonly designed as advertisements of commodities, events, etc. The advertisers customarily furnish the posters which are to be mounted on the billboards, and the mounting or posting is done by still other individuals or concerns whose services are employed 45 for that purpose. Of course, in addition to location, the general appearance and character of bill boards is an important factor in rendering them desirable from the standpoint of the advertiser and hence consistently remunerative to 50 their proprietors and, moreover, the character and neatness of their appearance are matters of public concern. As a consequence, for the purpose of contributing to the appearance of billboards, the proprietors have resorted to various 55

expedients such as the provision of wooden frames or borders around the area upon which the display posters are mounted. Such wooden borders, however, are subject to deterioration by the elements and, when made of wood or metal, are expensive to maintain because of the necessity of painting them periodically.

The present invention eliminates the necessity for such wooden or permanent borders or frames, and at the same time affords means for maintaining a higher and more consistent standard of appearance in billboard installations, but at a substantially lower expense.

The nature of the invention will now be described by reference to the examples shown in the drawings, in which it is to be observed that Fig. 1 represents a billboard installation comprising a relatively rigid foundation member, in the nature of a wall or the like, which affords a plane surface upon which a poster 10 is pasted. As seen in this figure, the poster is displayed within a rectangular frame or border, which gives the display a finished appearance and contributes to the installation an aspect of stability. It is with this frame that the present invention is primarily concerned.

For forming this frame, I provide what will hereinafter be referred to as margin strips, which are strips of poster paper of any of the kinds commonly used for billboard posters or the like, or other suitable sheet material. These strips are of substantial width, for example, of the order of twenty-six inches, and may vary as to length. In Fig. 1 they are represented as top and bottom strips designated by the reference numeral 12, and end strips designated by the reference numeral 12'. Upon areas of suitable width adjacent one margin, the strips are printed or lithographed with a border portion 12a of a character such as to represent a molding or a portion of a frame, which printing may be such as to give said portion the appearance of being raised or embossed, or of cove or other form. The balance of the width of the strips is left blank, or may be tinted or decorated in other appropriate fashion, to afford blanking areas 12b. The various different sections, such as the top and bottom strips 12 and the end strips 12', may all be sections of what was printed originally as a continuous strip or web and, in order to form the frame for the billboard display, these strips are pasted onto the plane wall or surface of the foundation member or other strips or sheets which previously may have been mounted upon it and which remain securely in place. Consequently, when reference is made to the foundation member or wall portion, it is to be understood that the term is to include also such additional layer or layers of paper or the like adhering to them and affording a suitable surface and place of attachment for the margin strips and poster. In order to facilitate the pasting up of the various parts, and to form the corners of the frame, the top and bottom strips 65 may be posted up first on the foundation member, and the end strips may be mitered or cut off at a 45° diagonal at their ends and overlapped upon the end portions of the top and bottom strips, as illustrated in Fig. 2. Of course, 70 this procedure may be reversed, viz., the end strips 12' posted up first, and the top and bottom strips mitered and pasted over their end portions. This posting up of the margin strips may be accomplished by use of the kinds of paste, brushes, etc., which are commonly employed for

bill posting. The printed or lithographed margin strips, however, have certain characteristics, which will be pointed out in connection with the following description of a method of manufacturing said strips.

The border area or frame-simulating portions of the margin strips are printed or lithographed from suitable printing members which are engraved or etched so as to produce the desired design in simulation of a frame portion or the like, and inks of a kind customarily used for the printing or lithographing of display posters may be employed. For the printing or lithographing of posters which are designed to be exposed out-of-doors, it is customary to use inks which have certain water-repellent characteristics. Inasmuch as it is necessary or most convenient, in the posting up of the margin strips, to overlap portions of the printed border, as at the mitered corners of the frame or at places where sections of the strip may be joined, it is of importance that the printed border portion be of a character such that the paste will adhere to it, in order that the superimposed strip portion may be securely pasted up. Accordingly, in preparation of the plates or printing members from which the border portions are printed, in cases where water-repellent inks are to be used, the design is produced by engraving or etching in such a fashion as to leave a substantial proportion of the area comprised within the design free, or substantially bare, of ink. This may be accomplished by employment of various sorts of engraving or etching technique in such fashion as to produce an appearance of continuity or solidarity in the printed design, with the proper shading to give the aspect of raised, embossed or recessed contour, but at the same time leave a substantial proportion of non-inked surface distributed across the area on which the design appears. One fashion in which this may be accomplished is by a line shading, such as is exemplified generally in Fig. 2, wherein the ink is applied in separated areas each of limited width and so arranged as to produce the desired surface contour aspect, but with non-inked, or substantially bare, areas of the paper between the inked areas. Another manner in which the desired results may be obtained is illustrated in Fig. 3, wherein the inked areas are arranged in a manner of stippling, varied in density or color in such fashion as to give the desired contour effect, but with a substantial proportion of the surface of the paper within the border area bare or devoid of ink. Various other types of technique may be employed to like effect, the desired or characterizing result being that within the area of the printed design itself, there are left distributed non-inked areas which represent a substantial proportion of the area of the design. Accordingly, when water-repellent inks are used for the printing of the design, these distributed bare areas remain in condition for effective adhesion of the kinds of water paste generally used in bill posting, thus making it possible to affix superimposed strip portions securely by that means. In this fashion it is made possible to post up the margin strips on the billboard by use of the same kind of paste and instrumentalities employed for the posting up of the poster, and to permit a fresh frame to be installed by the bill posters at the time each new poster is put up. Of course, the colors and designs of the borders may be selected to match or properly harmonize with or contrast with the

colors, designs and subject matter of the posters in respective postings.

For purpose of economy I prefer to print the margin strips from a continuous web or long strip of paper, and to facilitate that operation I form the printing or impression members as cylinders or cylindrical tubes, such as illustrated for example in Fig. 5. These are engraved on their peripheries so as to form a continuous or uninterrupted printing face effective to print the design or portions of the design, as a continuous streak or stripe. For the purpose of obtaining desired depth shading effects or other characteristics in the printed design, a plurality of printing members may be employed to apply different portions of the design to the web, one after another.

In order to render the operation still more economical, I prefer to print the margin strips in multiple, so as to produce the border design, or a portion thereof, in duplicate with the outer marginal portions of the two designs in adjacent relationship on the web. Accordingly, when printed in this fashion, the printed web will be of the character illustrated in Fig. 7, viz., with two juxtaposed frame portions 12a running longitudinally of it and with blanking portions 12b extending outwardly therefrom toward the web margins, forming, in effect, margin strips joined along the line x-x. After being thus printed, the web is fed to a cutter 26 which severs it longitudinally along the line x-x, thus separating it into the two margin strips, and these proceed to respective reels 27 on which the strips, or appropriate lengths thereof, are wound into rolls 12n of the desired size.

Of course, the margin strip sections need not necessarily be wound into rolls, as they may be folded, if desired. However, the roll arrangement is of greater convenience in most instances, as it facilitates the handling and application of the margin strips. One fashion in which such strips may be applied to the billboards from a roll is illustrated in Fig. 4. In this procedure, a roll 12n is placed on a spindle 30 which, with a suitable support 31 for the roll, is carried on a handle 32. After paste has been applied to the proper area of the billboard, as along its upper marginal portion, the roll is elevated by means of the handle, the strip pressed against the prepared portion of the billboard and then unrolled lengthwise thereof against the pasted area, and the unwound portion of the strip torn off from the roll when the end of the billboard is reached. Then the detached portion, which is held by the still wet paste on the billboard, is smoothed down by means of a brush in the customary fashion. A more detailed description of the manner of installing or applying the margin strips in the billboard installation is described in my copending application Serial No. 252,339, filed on even date herewith. Following the posting up of the margin strip to form the frame as there described, the poster 10 is posted up, its marginal portions being overlapped and pasted against the inward portions of the blanking areas 12b of the margin strips.

For the purpose of facilitating the accurate matching of portions of the frame or border design where sections of the margin strips are joined to one another, as for example at the miter portions 12c, it is desirable that the border or frame design be printed on the paper in such relationship that it runs longitudinally with the grain of

the paper. This is due to the fact that when wet with paste and manipulated with the posting brush, various papers are prone to stretch considerably in a direction transversely of the grain of the paper, whereas the stretch longitudinally of the grain is comparatively slight. Accordingly, by having the frame or border running longitudinally of the grain, the opportunity for stretching, which would be considerable in a long strip, is minimized.

From the foregoing it will be ascertained that the novel margin strip or combined framing and blanking strip, forming the subject matter of my present invention, effect substantial economies in billboard installation maintenance, and affords means for effecting very substantial improvement in their appearance, at a substantial saving in expense, and that said strip is of a character facilitating its being produced very economically and in a condition such that it, including portions which may be superimposed, may be securely maintained in proper relationship in a billboard installation by a paste of the sort customarily employed for mounting posters in such installations.

I claim:

1. Means for framing posters or the like on billboards, comprising a strip of paper having a border area along one margin thereof printed to simulate a moulding portion of a poster frame and having a blanking portion of substantial width contrasting in appearance with said border area and extending alongside it and between it and the opposite margin of the strip to simulate a mat portion associated with the moulding portion, said strip being adapted to be affixed flat upon a billboard surface by means of paste.

2. Means for framing posters or the like on billboards, comprising a strip of paper having a border area along one margin thereof printed to simulate a moulding portion of a frame and having a blanking portion of substantial width extending alongside said border area and between it and the opposite margin of the strip and of an appearance contrasting with the moulding portion, a substantial proportion of the paper surface within said border area being free of ink so as to enable a sheet to be securely affixed thereto by means of bill posting paste.

3. Means for framing posters or the like on billboards, comprising a strip of paper having a border area along one margin thereof printed to simulate a moulding portion of a frame and having a non-printed blanking portion of substantial width extending alongside said border area and between it and the opposite margin of the strip, a substantial proportion of the paper surface within said border area being free of ink so as to enable a sheet to be securely affixed thereto by means of bill posting paste and said ink-free parts within the border area being distributed throughout the same.

4. Means for framing posters or the like on billboards, comprising a strip of paper having a border area along one margin thereof printed with water-repellent ink to simulate a moulding portion of a frame extending longitudinally of the strip and having a contrasting blanking portion of substantial width extending alongside said border area and between it and the opposite margin of the strip, said strip being adapted to be affixed flat upon a billboard surface by means of paste, there being portions in scattered distribution within the border area which are bare of water-

repellent ink so that a sheet may be securely affixed in overlapped position upon the border area by means of a water paste.

- 5 5. Means for framing posters or the like on billboards, comprising a strip of paper having a border area along one margin thereof printed to simulate a moulding portion of a frame and having a blanking portion of substantial width extending alongside said border area and between it and the opposite margin of the strip in simulation of a mat portion associated with the moulding portion, said strip being wound into a roll with the printed side thereof inside, so that the strip may be affixed flat upon the surface of a billboard, to simulate an extensive moulding with an associated mat, by rolling the roll along and in contact with a portion of such surface bearing moist
- 10
- 15

paste, in such manner as to unwind and press the strip against such surface.

- 6 6. Means for framing posters or the like on billboards, comprising a strip of paper having an area thereof printed with water-repellent ink to simulate a moulding portion of a frame extending continuously longitudinally of the strip, said strip being adapted to be affixed flat upon a billboard surface by means of paste, and there being left within said printed area and distributed both crosswise and lengthwise thereof portions of the paper which are bare of water-repellent ink so that a similar paper sheet may be securely affixed in overlapped position upon said printed area at any location longitudinally thereof by means of a water paste.
